US0D1112057S

(12) **United States Design Patent** (10) Patent No.: **US D1,112,057 S**
(45) Date of Patent: ** Feb. 10, 2026

(54) **UNIVERSAL BASE FOR ELECTRIC TOOTHBRUSH**

(71) Applicant: **Braun GmbH**, Kronberg (DE)

(72) Inventors: **Fritz Schubert**, Bad Camberg (DE);
Dominik Langhammer, Kronberg im Taunus (DE); **Robert Schmidt**, Liederbach am Taunus (DE)

(73) Assignee: **Braun GmbH**, Kronberg (DE)

(**) Term: **15 Years**

(21) Appl. No.: **29/802,651**

(22) Filed: **Aug. 6, 2021**

(51) LOC (15) Cl. **13-02**

(52) U.S. Cl.

USPC **D13/108**

(57)

CLAIM

The ornamental design for a universal base for electric toothbrush, as shown and described.

DESCRIPTION

FIG. 1 is a perspective view of a first embodiment of a universal base for electric toothbrush;

FIG. 2 is a front view thereof;

FIG. 3 is a right-side view thereof;

FIG. 4 is a rear view thereof;

FIG. 5 is a left-side view thereof;

FIG. 6 is a top plan view thereof; and,

FIG. 7 is a bottom view thereof.

Broken lines are used in the drawings to designate parts of the universal base for electric toothbrush that form no part of the claim.

1 Claim, 5 Drawing Sheets
